CLAIM

The ornamental design for a bearing gadget, as shown and described.

DESCRIPTION

FIG. 1 is a top, front, right side perspective view of a bearing gadget according to a first embodiment of my new design; FIG. 2 is both a front elevation view and a rear elevation view thereof;

FIG. 3 is both a left side elevation view and a right side elevation view thereof;

FIG. 4 is both a top plan view and a bottom plan view thereof;

FIG. 5 is a top, front, right side perspective view of a second embodiment thereof;

FIG. 6 is both a front elevation view and a rear elevation view thereof;

FIG. 7 is both a left side elevation view and a right side elevation view thereof; and,

FIG. 8 is both a top plan view and a bottom plan view thereof.

The broken lines in the figures depict portions of the bearing gadget that form no part of the claimed design.
